UNITED STATES PATENT OFFICE

LOUIS WEITZMAN, OF NEW YORK, N. Y.

DESIGN FOR AN AUTOMOBILE TRUNK OR THE LIKE

Application filed February 13, 1931. Serial No. 38,641. Term of patent 3½ years.

To all whom it may concern:

Be it known, that I, LOUIS WEITZMAN, a citizen of the United States, residing in the county of Bronx, city and State of New York, have invented a new, original, and ornamental Design for an Automobile Trunk or the like, of which the following is a specification, reference being had to the accompanying drawings, forming part thereof, wherein—

Figure 1 is a perspective view of an automobile trunk embodying my design.

Fig. 2 is a section taken along the plane of the line 2—2 of Fig. 1.

The essential features of my design consist in the shape of the trunk; in the disposition of the metallic bands *a*, *a*, which extend

across the lid and the front of the body of the trunk in equally spaced relation to the ends thereof; in the beads *b*, *b*, between which the metallic bands are inlaid; in the relation of said metallic bands and said beads with respect to the locks *c*, *c*; and in the color contrast produced by the metallic bands *a*, *a*, with the color of the fabric which covers the trunk.

I claim:

The ornamental design for an automobile trunk or the like substantially as shown and described.

In witness whereof, I have hereunto set my name this 11th day of February, 1931.

LOUIS WEITZMAN.
